UNITED STATES PATENT OFFICE.

JOHAN M. ANDERSEN, OF BOSTON, MASSACHUSETTS.

DESIGN FOR A HANGER.

SPECIFICATION forming part of Design No. 23,245, dated May 1, 1894.

Application filed February 23, 1894. Serial No. 501,310. Term of patent 14 years.

To all whom it may concern:

Be it known that I, JOHAN M. ANDERSEN, residing in Boston, in the county of Suffolk and State of Massachusetts, have invented and produced a new and original Design for a Single Pull-Off, of which the following description, in connection with the accompanying drawings, is a specification, like letters on the drawings representing like parts.

10 The design relates to a single pull off employed to support an insulated hanger for the trolley wire employed in the overhead system of electric railways, and consists in a single pull off distinguished by its peculiar 15 shape, which will be hereinafter set forth and claimed.

Figure 1 shows in front elevation a single pull off embodying my design, and Fig. 2, a side elevation of the single pull off looking 20 toward the left in Fig. 1.

The leading feature of my design consists in a body portion *a* made in the shape of a frustum of a cone, and a single vertically disposed curved arm *a'* integral with the body 25 *a* and having its junction with the said body extend from near the base to near the top of the body, so that the arm *a'* has a wide appearance where it is joined to the body *a*.

The vertically disposed arm *a'* has its upper edge extended in a curve to below the bottom 30 of the body *a* and the lower curved edge of the said arm is reinforced by curved strengthening webs or ribs *b* on opposite sides of the vertically disposed arm *a'* and the said ribs or webs are made wider at their point of juncture with the body *a* and taper downwardly 35 in conformity with the curved lower edge of the arm *a'*, and form at the end of the said arm an eye *b'* of greater thickness than the vertically disposed arm *a'*. The reinforced vertically disposed arm extends a considerable distance below the bottom of the frustum shaped body *a*. The frustum shaped body *a* is provided with a cap *d* fitted upon a threaded neck *d'* of the said body, and the latter is provided with a thickened edge *d''* at its base. 45

I claim—

The design for a single pulloff herein shown and described.

In testimony whereof I have signed my 50 name to this specification in the presence of two subscribing witnesses.

JOHAN M. ANDERSEN.
